BOTTLED BEVERAGE COOLER

Knud J. Helsing, Longmeadow, Mass., assignor to
Westinghouse Electric Corporation, East Pittsburgh, Pa., a corporation of Pennsylvania

Application April 9, 1952, Serial No. 281,299

2 Claims. (Cl. 62—102)

1

This invention relates to refrigerating apparatus and more particularly to dry coolers for bottled beverages.

It is an object of this invention to provide an improved bottled beverage cooler of the so-called "up-right" variety. In this type of cooler, the bottles to be cooled are stored on vertically spaced shelves disposed within a heat insulated cabinet structure. The shelves are generally inclined to permit the bottles stored thereon to roll by gravity to one side of the cabinet, from which they are removed, as required, through one or more small serving openings in the front of the cabinet. As the end bottle is removed from each shelf the remaining bottles roll down the incline to present another bottle adjacent the serving opening for removal. The bottles are cooled by the circulation of cold air within the cabinet and it is another object of this invention to provide an improved air circulating system for beverage coolers of the above described type.

A further object of my invention is to provide rapid cooling of those bottles which have been so placed in the cooler as to be first available for serving.

A still further object of my invention is to control the flow of cool air within the cooler and thereby compensate for the additional heat leakage into that region of the cabinet adjacent the serving opening.

These and other objects are effected by my invention as will be apparent from the following description taken in connection with the accompanying drawings, forming a part of this application, in which:

Fig. 1 is a perspective view of a bottled beverage cooler embodying my invention;

Fig. 2 is a front view of the cooler illustrated in Fig. 1 with the door open and portions of the structure cut away to show details of construction;

Fig. 3 is an end view of my improved beverage cooler with portions of the cabinet structure broken away to show the interior of the cooling chamber; and

Fig. 4 is a horizontal cross sectional view of the cooler taken generally along the line IV—IV of Fig. 2, but with the door closed.

Referring to the drawings, the numeral 10 designates generally a refrigerator cabinet divided into an upper insulated bottle cooling chamber or compartment 11 and a lower machinery compartment 12. The front of both the bottle cooling compartment 11 and machinery compartment 12 are closed by an insulated door 13 hinged at 14

to the cabinet 10. The door 13 is opened and closed by a handle 15 connected to a suitable latching mechanism for holding the door in its closed position. The latching mechanism is not shown for the sake of brevity. The bottle cooling compartment 11 comprises a top wall 16, a bottom wall 17, a back wall 18 and side walls 19 and 20.

Disposed within the bottle cooling compartment 11 are a number of vertically-spaced inclined shelves 21 arranged to support bottled beverages 22 in a horizontal position with their cap ends forward. The shelves 21 are supported on the cabinet side walls 19 and 20 in any suitable manner as by bracket members 23. The shelves 21 are formed preferably of sheet metal and are provided with an upturned flange 24 at their rear edges to engage and position the rear end of the bottles 22. The shelves 21 may also be provided with a downturned flange 25 on their forward edge if additional strength is desired. As shown in Figs. 3 and 4, the shelves 21 may be so constructed as to be movable forward or backward on the flange members 23 in order that they may accommodate various length bottles. It will be noted that the width of the shelves is such as to leave a space between the rear edge of the shelf and the cabinet back wall 18 and between the front edge of the shelf and the cabinet front wall 30 or door 13. This spacing provides passages for the flow of cooling air to and from the bottle as will hereinafter be described.

As best shown in Fig. 2, the shelves 21 are inclined downwardly toward the compartment side wall 19. It will be thus evident that any bottles placed on the shelves 21 would tend to roll by gravity toward the side wall 19. To permit removal of the bottles from the cooler, a vending opening 26 is provided in and along the left hand edge of the cabinet door 13. This vending opening 26 is closed by a door 27 which is hinged at 28 to the cabinet door 13. The peripheral edge of the opening 26 is provided with a gasket member 29 which is engaged by the vending door 27 when in its closed position to prevent warm air from entering the cooling chamber 11. The door 27 is provided with a transparent portion 30 to permit the contents of the cooler to be ascertained without the necessity for opening the vending door 27. The vending door 27 is also provided with a handle 31 which is associated with suitable latching mechanism, the latter not being shown for the sake of brevity.

Secured to the lower wall 17 of the cooling

compartment 11 and disposed to one side thereof is a cooling unit 32. While the cooling unit may be of any suitable construction, I have illustrated a generally rectangular unit comprising a refrigerated coil 33 having a number of heat transfer fins 34 mounted thereon. As shown in Figs. 3 and 4, the cooling unit 32 is mounted in a forward portion of the cooling compartment 11 and beneath the lowermost of the shelves 21. Directly behind the cooling unit 32 is mounted a motor driven fan 35 which is supported on the compartment bottom wall 17 by a bracket 36. The fan 35 is surrounded by a shroud 37 having the same rectangular configuration as the air path through the cooling unit 32. The shroud 37 extends from the cooling unit 32 to the rear wall 18 of the cooling compartment 11 and is provided with an elongated opening 38 in its upper surface 39 adjacent the back wall 18.

The cold air pulled through the cooling unit 32 by the fan 35 is discharged upwardly through opening 38 in the fan shroud 37 and passes into the upper portions of the cooling chamber 11 through the air passage space between the rear edges of the shelves 21 and the compartment back wall 18. This cold air then passes forward between the shelves 21, over the bottles 22 on the shelves and returns to the cooling unit via the air passage provided between the front edges of the shelves 21 and the compartment front door 13. In order to prevent the cold air discharged by the fan 35 from passing beneath the lowermost bottle shelf 21, a baffle 40 is secured by any suitable means, as by screws 43a, to the compartment back wall 18. The baffle 40 is positioned parallel to and extends forward to the rear edge of the lowermost shelf 21. The baffle 40 is also provided with a turned down end portion 41 which engages a corner of the fan shroud 37.

Whenever the cooler is loaded with a fresh supply of warm bottles, it is desirable that those bottles which are to be first consumed, that is, those bottles near the side wall 19 and behind the vending door 27, be cooled first. To insure such operation, there is provided above the fan discharge opening 38, an inclined deflector 42 for directing the air coming from the cooling unit 32 generally toward the side wall 19 and hence over the bottles which are to be first consumed. The baffle 42 is secured to the back wall 18 of the cooling chamber by any suitable means, such as by screws 43, and extends forward into the air passage space between the shelves 21 and the back wall 18. The angle of inclination of the baffle 42 of course depends upon the design and arrangement of the cooler in which it is employed and may be varied to suit the requirements of different coolers. The arrows within the cooling chamber 11 of the various figures of the drawings indicate generally the path taken by the cooling air when circulated within the cooler.

The directing of the major portion of the cooling air over the bottles adjacent the serving opening additionally compensates for any heat leakage into the cabinet resulting from the inflow of warm air during periods when the serving door 27 is open. There is also a tendency for additional heat to leak around and through the transparent serving door 27 even when it is closed. This additional heat leakage is fully compensated for by the increased flow of cooling air to that portion of the refrigerated chamber.

The tube 33 of the cooling unit 32 is supplied with a refrigerant from conventional mechanical

refrigerating equipment located within the machinery compartment 12. This refrigerating equipment comprises generally a hermetically-sealed casing 44 which encloses a refrigerant compressor and a motor for driving the same, neither of which are shown. A condenser 45 condenses the refrigerant vapor compressed by the compressor which is then conveyed to the cooling unit 32 through a capillary tube 46. The vaporized refrigerant returns to the compressor through a conduit 47.

The cooling unit 32, in lowering the temperature of the air within the cooling chamber 11, will condense from this air a quantity of water which is removed from the cooling chamber by a drain and trap arrangement 48 extending through the bottom wall 17 of the cooling compartment. This water is discharged into a pan or tray 49 within the machinery compartment 12 and is vaporized by the heat from the refrigerating equipment.

It will be apparent from the above that this invention provides a bottled beverage cooler having many novel advantages and features. The cooler herein described is capable of efficiently cooling a large number of bottled beverages and of storing them in a manner such as to permit ready removal of any particular brand of bottled beverage though a number of brands are stored therein. The invention further provides for rapid cooling of those bottles which are to be consumed first after the cooler has been filled with warm bottles. Furthermore, provision is made for increasing the flow of cool air into those regions of the cooling chamber which are more likely to be subjected to an increased heat load from outside the cabinet.

While I have shown my invention in but one form, it will be obvious to those skilled in the art that it is not so limited, but is susceptible of various changes and modifications without departing from the spirit thereof.

What I claim is:

1. In a cooler for bottled beverages, the combination of an insulated cabinet structure comprising top, bottom, back and side walls and defining a cooling chamber having an opening in the front thereof, a first insulated door for closing said opening, said first door having an opening therein providing access to said chamber, a second door for closing the opening in said first door, a plurality of vertically spaced inclined shelves disposed within said chamber, the inclination of said shelves being such as to cause bottled beverages placed thereon to roll to a portion of the shelves behind the access opening in said first door, said shelves being intermediate and spaced from the first door and rear wall of said cabinet structure to provide a pair of air passages in said chamber, a cooling unit disposed within said chamber, means for circulating air over said cooling unit, through one of said pair of passages, over the bottled beverages on said shelves, through the other of said pair of passages and back to said cooling unit, and a deflector positioned within said one air passage and arranged to direct at least a portion of the air passing over said cooling unit to a region of the chamber behind said access opening.

2. In a cooler for bottled beverages, the combination of an insulated cabinet structure having top, bottom, back and side walls and a front wall comprising a door, said cabinet structure defining a cooling chamber, said door having an opening therein providing access to a region of

5

said chamber, means for closing said opening, a plurality of vertically spaced inclined shelves disposed within said chamber and adapted to receive the bottled beverages to be cooled, the inclination of said shelves being such as to permit bottled beverages placed thereon to roll by gravity to a position behind said access opening, said shelves being intermediate and spaced from the front and rear walls of said cabinet structure to provide front and rear air passages in said chamber, a cooling unit disposed within said chamber, air circulating means within said chamber for circulating air over said cooling unit and into

5 said rear air passage and a deflector disposed within said rear air passage for directing at least a portion of the air flowing through said passage to the region of said chamber accessible through said opening.
